Specification for Design.

Patented Oct. 26, 1915.

Application filed December 28, 1914. Serial No. 879,407. Term of patent 14 years.

To all whom it may concern:

Be it known that I, THOMAS A. DE VILBISS, a citizen of the United States, residing at Toledo, in the county of Lucas and State of Ohio, have invented a new, original, and ornamental Design for a Coupling for the Air-Tube and Heelpiece of an Atomizer, of which the following is a specification, reference being had to the accompanying drawing, forming a part thereof.

The figure is a perspective view of a cou-

pling for the air tube and heel piece of an atomizer showing my new design.

I claim:

The ornamental design for a coupling for the air tube and heel piece of an atomizer, substantially as shown.

THOMAS A. DE VILBISS.
